UNITED STATES PATENT OFFICE.

DAISY DEARMAN, OF PARIS, FRANCE.

DESIGN FOR A DOLL'S HEAD.

Application filed March 28, 1924. Serial No. 9,088. Term of patent 7 years.

To all whom it may concern:

Be it known that I, DAISY DEARMAN, a British subject, and a citizen of the Commonwealth of Australia, residing at Paris, France, have invented a new, original, and ornamental Design for a Doll's Head, of which the following is a specification, reference being had to the accompanying drawing, forming part thereof.

The figure is a front view of the upper part of a doll's head, showing my new and original design.

The fluffy material at the side of the doll's head represents fluffy, silky hair expanding from under the cap.

I claim:

The ornamental design for a doll's head, substantially as shown.

New York, March 26, 1924.

DAISY DEARMAN.
